US0D1066915S

(12) United States Design Patent (10) Patent No.: US D1,066,915 S
(45) Date of Patent:  Mar. 18, 2025

(54) HANDLE FOR ELECTRIC TOOTHBRUSH

(71) Applicant: GUANGZHOU STARS PULSE CO., LTD, Guangzhou (CN)

(72) Inventors: Kebi Ding, Guangdong (CN); You Shen, Guangdong (CN)

(73) Assignee: Guangzhou Stars Pulse Co., Ltd, Guangzhou (CN)

() Term: 15 Years

(21) Appl. No.: 35/519,058

(22) Filed: Sep. 15, 2023

(80) Hague Agreement Data

Int. Filing Date: Sep. 15, 2023
Int. Reg. No.: DM/233044
Int. Reg. Date: Sep. 15, 2023
Int. Reg. Pub. Date: Nov. 17, 2023

(30) Foreign Application Priority Data

Mar. 16, 2023 (CN) 202330125539.X
Mar. 24, 2023 (CN) 202330149243.1

(57) CLAIM

The ornamental design for a handle for electric toothbrush as shown and described.

DESCRIPTION

2. Handle for electric toothbrush
6. Handle for electric toothbrush
7. Handle for electric toothbrush
- 2.1: Perspective
- 2.2: Perspective
- 2.3: Front
- 2.4: Back
- 2.5: Left
- 2.6: Right
- 2.7: Top
- 2.8: Bottom
- 6.1: Perspective
- 6.2: Front
- 6.3: Left
- 6.4: Right
- 6.5: Top
- 6.6: Bottom
- 7.1: Perspective
- 7.2: Front
- 7.3: Left
- 7.4: Right
- 7.5: Top
- 7.6: Bottom

The broken lines in the drawings illustrate portions of the handle for electric toothbrush that form no part of the claimed design; the oblique shading lines in the drawings indicate a transparent surface, a translucent surface, a screen, or a mirror surface.
